CLAIM

The ornamental design for a data-processing system, as shown and described.

DESCRIPTION

FIG. 1 is a perspective view of one embodiment of a data-processing system embodying our new design;

FIG. 2 is a front view thereof;

FIG. 3 is a rear view thereof;

FIG. 4 is a right side view thereof, the left side view being a mirror image of the right side view;

FIG. 5 is a top view thereof;

FIG. 6 is a bottom view thereof;

FIG. 7 is a perspective view of another embodiment of a data-processing system embodying our new design;

FIG. 8 is a front view thereof;

FIG. 9 is a rear view thereof;

FIG. 10 is a right side view thereof, the left side view being a mirror image of the right side view;

FIG. 11 is a top view thereof; and,

FIG. 12 is a bottom view thereof.

The broken lines show environment and form no part of the claimed design.
